US00D330596S

United States Patent [19]

Frenkel et al.

[11] Patent Number: Des. 330,596

[45] Date of Patent: ** Oct. 27, 1992

[54] DIAGNOSTIC IMMUNOASSAY MACHINE

[75] Inventors: Dina Frenkel, Plano, Tex.; Fareed Kureshy, Westwood, Mass.; William J. Lawrence, Garland, Tex.

[73] Assignee: PB Diagnostic Systems, Inc., Westwood, Mass.

[**] Term: 14 Years

[21] Appl. No.: 514,339

[22] Filed: Apr. 24, 1990

[52] U.S. Cl. D24/186

[58] Field of Search D24/186, 216, 232, 231; 422/62, 63, 64, 68, 99, 101

[57] CLAIM

The ornamental design for a diagnostic immunoassay machine, as shown and described.

DESCRIPTION

FIG. 1 is a perspective view of a diagnostic immunoassay machine showing our new design;

FIG. 2 is a left side elevational view thereof;

FIG. 3 is a right side elevational view thereof;

FIG. 4 is a rear elevational view thereof;

FIG. 5 is a front elevational view thereof;

FIG. 6 is a bottom plan view thereof; and,

FIG. 7 is a top plan view thereof.

FIG. 1

FIG. 2

FIG. 3

FIG. 4

FIG. 5

FIG. 6

FIG. 7
